UNITED STATES PATENT OFFICE.

EDWARD D. CONKLIN, OF NEWARK, NEW JERSEY, ASSIGNOR TO THE WHITEHEAD & HOAG COMPANY, OF NEWARK, NEW JERSEY, A CORPORATION OF NEW JERSEY.

CAP FOR KEYS OF TYPE-WRITING AND ANALOGOUS MACHINES.

No. 870,275.

Specification of Letters Patent.

Patented Nov. 5, 1907.

Application filed June 25, 1906. Serial No. 323,316.

To all whom it may concern:

Be it known that I, EDWARD D. CONKLIN, of Newark, in the county of Essex, in the State of New Jersey, have invented new and useful Improvements in Caps for Keys of Type-Writing and Analogous Machines, of which the following, taken in connection with the accompanying drawings, is a full, clear, and exact description.

This invention relates to certain improvements in keys for typewriting and analogous machines, and refers more particularly to the finger pieces upon which the characters are printed or impressed. These characters are usually printed upon the upper faces of the keys and soon become obliterated by use.

15 The essential object, therefore, of my present invention is to render the printed character permanent by covering it with a transparent cap of comparatively inexpensive material.

20 The form of the key and cap is immaterial, the essential purpose being to print the character either directly upon the key, or upon any opaque or other body of suitable material carried by the key, and to cover the printed character with a transparent or semi-transparent cap or coating for the purpose of protecting the 25 print from obliteration.

In the drawings—Figure 1 is a perspective view of a key embodying my invention. Fig. 2 is an elevation of the key proper, showing the cap in section as composed of an inner layer of suitable material upon which 30 the character is printed, and an outer layer of transparent material, such as pyroxylin or other equivalent substance. Fig. 3 is a perspective view of the detached cap seen in Figs. 1 and 2. Fig. 4 is a perspective view of a key having the character printed directly upon its 35 upper face. Fig. 5 is a perspective view of a transparent cap adapted to be placed upon the key seen in Fig. 4, to cover and protect the printed character.

The key, as—1—, may be of any desired form, size or 40 material, and is shown as provided with a stem—2—, adapted to be fitted in the key-lever, not shown, although any suitable fastening means may be employed for attaching the main body of the key, as—1—, to the lever.

45 The part—1—will be hereinafter designated as the base of the key, and upon this base is fitted a cap—3—, which, as shown in Figs. 1, 2 and 3, is composed of an inner layer—4—of thin comparatively inexpensive material, as paper or other suitable material, upon which the character is printed, and an outer layer—5— 50 of transparent or semi-transparent material, such as pyroxylin or its equivalent.

The inner layer is preferably opaque and cup-shaped to fit upon the top and sides of the base—1—, and the outer transparent layer—5— is of similar shape and is 55 fitted upon the top and sides of the inner layer—4—.

the parts—4— and—5— being usually secured together to form a unitary cap capable of being made as a separate article of manufacture and applied to the form of key for which it is intended, it being understood that the form of the cap is made to correspond with that of the key which may be round, oval, or multi-sided, as shown. This cap—3— is formed with a marginal flange—6— fitting closely upon the sides of the base—1— to retain the cap against lateral displacement, and this flange may be formed upon either the outer or inner 60 layer, or upon both layers, as shown in Fig. 2.

The outer transparent body—5— may be a mere coating upon the outer surface of the inner layer—4— upon which the character is printed without departing from the spirit of my invention, or as shown in Figs. 4 and 5, the character may be printed directly upon the top face of the base, as—7—, and covered by a transparent cap—8—, shown in Fig. 5, in which case, the inner opaque body or layer—4— would be omitted, and the transparent body made of sufficient thickness to 70 withstand the usage to which it would be subjected. The essential purpose, however, of my invention is to produce a comparatively inexpensive cap as a new article of manufacture, in which the character is printed on a body of paper or pasteboard of suitable form, and 75 then covered with a body of transparent celluloid or equivalent material of similar form, the two bodies being permanently secured together. The complete cap is then adapted to be adhesively or otherwise secured to the body of the key, which is usually made of composition material. In other words, it is my purpose to manufacture these caps separately, in various forms, for use on different styles of keys, each cap bearing an erasable character printed upon an inner layer of paper, or equivalent cheap material, and covered by a coating 80 or layer of transparent material, as celluloid, through 85 which the character is clearly visible.

What I claim:

1. A cap for typewriting-machine keys comprising two cups adhesively secured together, one within the other, the inner cup bearing the printed character and the outer cup being transparent to render said character visible therethrough and to protect said character from obliteration. 95

2. A cap for typewriting machine keys comprising an inner cup of paper bearing the printed character, and an outer cup of transparent pyroxylin material fitting upon and adhesively secured to the inner cup. 100

3. In a key for typewriting machines, a base portion, a paper cup fitted upon and adhesively secured to the base, and a transparent cup fitted upon and adhesively secured 105 to the paper cup.

In witness whereof I have hereunto set my hand this 22nd day of June 1906.

EDWARD D. CONKLIN.

Witnesses:

HENRY KEIPEE,
F. P. CRANE.
